HARRY S. VINCENT, OF RIDGEWOOD, AND WILLIAM P. STEELE, OF PALISADE, NEW JERSEY.

THROTTLE-VALVE MECHANISM FOR LOCOMOTIVES.

1,227,096.

Specification of Letters Patent. Patented May 22, 1917.

Application filed December 8, 1916. Serial No. 135,871.

To all whom it may concern:

Be it known that we, HARRY S. VINCENT, of Ridgewood, in the county of Bergen and State of New Jersey, and WILLIAM P. STEELE, of Palisade, in the county of Bergen and State of New Jersey, have jointly invented a certain new and useful Improvement in Throttle-Valve Mechanism for Locomotives, of which improvement the following is a specification.

Our invention relates to throttle valve operating mechanism of the class or type, long known in the art, in which the connections between the throttle shaft and throttle lever extend entirely outside of the boiler, and its object is to provide means whereby undue strain upon the connecting members, and accidental and undesired opening of the throttle valve, due, in each case, to unequal expansion and contraction of the exposed connecting members and of the boiler, respectively, when the temperature of the latter is materially raised or lowered, may be effectually prevented.

The improvement claimed is hereinafter fully set forth.

In the accompanying drawings: Figure 1 is a side view, in elevation, of the upper rear portion of a locomotive boiler, illustrating an application of our invention; Fig. 2, a vertical transverse section, on the line $x-x$ of Fig. 1; Fig. 3, a side view, in elevation and on an enlarged scale, of the locking mechanism proper; Fig. 4, a horizontal section, on the line $y-y$, of Fig. 1, and; Fig. 5, a similar section, on the line $z-z$ of Fig. 2.

In throttle valve operating mechanism of the class to which our invention relates, particularly as applied in large locomotive boilers of the present standard types, a considerable distance ordinarily intervenes between the throttle valve dome and the throttle lever, which is supported at or near the back head of the boiler, and the throttle rod, which leads, externally to the boiler, from the throttle lever in the cab to the throttle valve dome, being exposed, throughout this distance, to the atmosphere, its expansion and contraction, under variations of atmospheric temperature, are materially less than those of the boiler, between its temperature when under steam and when cooled to that of the atmosphere after the fire has been drawn. As a result of this difference

in expansion and contraction, it has been found, in practice, that the expansion of the boiler, when heated, is sufficiently greater than that of the throttle rod, to cause the throttle valve to be accidentally opened, thereby causing the unintended and unexpected movement of the locomotive, from which material damage has resulted. Another objection which is encountered in operating mechanism of the type referred to, is the imposition of undue stress and buckling tendency on the parts, by reason of the greater degree of contraction of the boiler in cooling.

Our invention, which is readily applicable in connection with any of the known forms of outside throttle valve operating mechanism, enables the objections above noted to be fully overcome, without involving complication or substantial expense of construction or maintenance.

In the practice of our invention, referring descriptively to the specific embodiment thereof which is herein exemplified, the throttle valve, 1, which may be of any suitable and preferred construction, is, as heretofore, seated in, and controls the passage of steam through, a vertical stand pipe, 2, which is supported in the dome, 3^a, of a locomotive boiler, 3, and is connected, at bottom, to a dry pipe or steam supply pipe, 4, leading to the engine cylinders. The throttle valve is raised and lowered, to admit steam to, and shut it off from, the dry pipe, by connections to a horizontal oscillatory throttle shaft, 7, journaled in a support, 8, secured to the outside of the dome, 3^a, and extending through a stuffing box, 8^a, therein.

The throttle shaft carries, on its outer end, an arm, 7^b, which is coupled, by a tubular throttle rod, 9, to a throttle lever, 12, pivotally connected to a support or stand, 10, secured to the boiler in such location within the cab of the locomotive as may render the throttle lever conveniently operable by the engineer, said lever swinging over a guide segment, 13, secured to the support, 10. In operating mechanisms of the various constructions known in the art prior to our invention, the segment is provided with a plurality of peripheral notches or teeth, adapted to be engaged by a latch which is pivoted to the throttle lever, for the purpose of locking the lever in any adjusted position. Under our invention, the

guide segment is plain or devoid of notches, and instead of the throttle lever being, as heretofore, locked by the engagement of a latch thereon with an adjacent segment, the 5 locking mechanism is located adjoining, and applied to, the throttle shaft, and is substantially of the following described construction and manner of operation.

A locking segment, 16, which is concentric 10 with the throttle shaft, 7, is secured to the support, 8, through which said shaft passes, said segment being peripherally notched or toothed. An arm, 7^c, projects from said shaft, diametrically opposite the arm, 7^b, to 15 which the tubular throttle rod, 9, is connected, said arm, 7^c, swinging over the rear face of the segment, 16, and having a guide block, 7^d, which is recessed to fit over said segment, secured to it by bolts, 7^e. A locking latch, 14^a, which is adapted to engage 20 the notches or teeth of the segment, 16, is coupled, by connections to be presently described, to the forward end of a latch rod, 14^b, which passes through the tubular throttle rod, 9, and is coupled, at its rear end, to 25 one of the arms of a bell crank or elbow lever, 14^c, journaled in a jaw fitting, 10^a, which is secured on the rear end of the rod, 9, and to which the throttle lever, 12, is 30 coupled. The opposite arm of the bell crank, 14^c, is coupled, by a link, 14^d, to a latch handle, 14, which is pivoted to the throttle lever, adjacent to its outer end. The relation of the pin which couples the 35 link to the bell crank, to that which couples the throttle lever to the jaw fitting, is such that when the former is moved outwardly by the latch handle, it becomes concentric with the latter.

40 The locking latch, 14^a, is secured to the upper end of a bar, 14^e, which is longitudinally slotted, to pass the bolts, 7^e, which connect the guide block, 7^d, to the arm, 7^c, and is guided, in its movements, by said block.

45 The lower end of the bar, 14^e, is coupled to a link, 14^f, which is centrally swelled and slotted to clear the nut on the outer end of the throttle shaft, and is coupled, at its lower end, to the lower arm of a bell crank 50 or elbow lever, 14^g, journaled in a jaw fitting, 10^b, which is secured on the forward end of the tubular throttle rod, 9, and to which the operating arm, 7^b, of the throttle shaft, is coupled. The upper arm of the bell crank lever is pivotally connected to the forward end of the latch rod, 14^b, before referred to. The relation of the coupling pin of the link and bell crank, to the 55 coupling pin of the jaw fitting and operating arm, is similar to that of the pins at the opposite end of the throttle rod.

In the operation of a mechanism constructed substantially as hereinbefore described, the depression of the latch handle, 65 14, by the operator, acting through the link,

14^d, moves the bell crank, 14^c, about its pivotal axis in the jaw, 10^a, bringing the pin in the rear arm of the bell crank approximately into register with the lever pin in the jaw, 10^a. The rearward motion thereby 70 imparted to the forward arm of the bell crank, is transmitted, through the link, 14^b, to the rear arm of the bell crank, 14^g, which is journaled in the jaw, 10^b. Swinging movement is thereby imparted to the other 75 arm of the bell crank, 14^g, sufficient to bring the pin at its end into register with the operating arm pin which couples the jaw, 10^b, with the arm, 7^b, and, through the link, 14^f, and bar, 14^e, simultaneously disengaging 80 the latch, 14^a, from the notches of the segment, 16. The latch is held in this released position, during the period that the throttle valve is being raised or lowered, by the throttle lever, 12, throttle rod, 9, arm, 85 7^b, shaft, 7, and their accessory parts. When the throttle valve has been moved to the desired position, the latch handle, 14, is released, thereby reversing the operation above described, and locking the throttle valve in 90 position by engaging the latch with the notches of the segment.

It will be seen that by reason of the locking mechanism proper being applied at the forward end of the throttle rod, and operating thereat, directly, to permit and prevent, respectively, movement of the throttle shaft as desired, instead of being, as heretofore, separated from said shaft by an intervening rod of considerable length, which is locked at its rear end and continuously subject to atmospheric temperature, the connections between the throttle lever and throttle shaft are wholly relieved from strains resultant upon the unequal degrees 105 of expansion and contraction of said connections and of the boiler, respectively. It will be equally clear that accidental and prejudicial opening of the throttle valve, by reason of such unequal expansion and contraction, will be absolutely prevented, the reason, in each case, being that the throttle lever is free to be moved, in either direction, over its guide segment, by the expansion and contraction of the boiler, thereby exempting 110 the throttle rod from strain and exerting no disturbing action on the locking mechanism.

Our invention, while readily applicable in connection with any of the known designs of outside operated throttle valves, is not 120 limited in application to any specific construction of throttle valves or of lever mechanism for the operation thereof.

We claim as our invention and desire to 125 secure by Letters Patent:

1. The combination, with a locomotive boiler, of a throttle valve; a throttle lever; connections, positively coupled throughout their length, interposed between the throttle valve and throttle lever, said connec- 130

5 tions extending longitudinally exterior to the boiler, and precluding variation of length through any admission of lost motion in operation; and means for locking said throttle valve in adjusted position without rendering said connections subject to strains.

2. The combination, with a locomotive boiler, of a throttle valve; a throttle lever; 10 connections, positively coupled throughout their length, interposed between the throttle valve and throttle lever, said connections extending longitudinally exterior to the boiler; and means for locking said throttle valve in adjusted position and permitting movement of the throttle lever and connections, relatively to the throttle valve, when said valve is locked.

3. The combination, with a locomotive 20 boiler, of a throttle valve; a throttle lever; connections, positively coupled throughout their length, interposed between the throttle valve and throttle lever, said connections extending longitudinally exterior to the boiler; and a locking mechanism located adjacent to, and operating on, the throttle valve.

4. The combination, with a locomotive boiler, of an internal throttle valve; a throttle lever; longitudinally extending connections interposed between said throttle valve and throttle lever; and a locking mechanism located and operating adjacent to the throttle valve end of said connections.

35 5. The combination, with a locomotive boiler, of a stand pipe supported in a steam dome thereof; a throttle valve manually operable to control said pipe; a lever support located exterior to the boiler and separated 40 by a longitudinal space from the stand pipe; a throttle lever pivoted to said support; connections coupling said lever to the throttle valve; and a locking mechanism supported adjacent to, and operating on, the throttle valve.

6. The combination, with a locomotive boiler, of a stand pipe supported in a steam dome thereof; a throttle valve controlling said pipe; a shaft support secured to the dome; an oscillatory throttle shaft journaled 50 in said support and extending to the exterior of the dome; connections coupling said shaft to the throttle valve; a lever support located exterior to the boiler and separated by a longitudinal space from the stand pipe; 55 a throttle lever pivoted to said support; connections coupling said lever to the throttle shaft; a peripherally toothed or notched locking segment secured to the shaft support; a latch adapted to engage said segment; a latch handle pivoted to the throttle lever; and connections coupling said latch handle to the latch.

7. The combination, with a locomotive boiler, of a stand pipe supported in a steam 65 dome thereof; a throttle valve controlling said pipe; a shaft support secured to the dome; an oscillatory throttle shaft journaled in said support and extending to the exterior of the dome; connections coupling said 70 shaft to the throttle valve; a lever support located exterior to the boiler and separated by a longitudinal space from the stand pipe; a throttle lever pivoted to said support; a tubular connection interposed between said 75 lever and the throttle shaft; a peripherally toothed or notched locking segment secured to the shaft support; a latch adapted to engage said segment; a latch handle pivoted to the throttle lever; bell crank levers journaled at opposite ends of the tubular connection and coupled to the latch and latch handle, respectively; and a rod extending through the tubular connection and coupled, at its ends, to said bell crank levers.
